United States Patent Office

Des. 227,185
Patented June 5, 1973

227,185

ASH TRAY

Robert W. Minners, Greenwich, Conn., assignor to Minners and Co., Inc., New York, N.Y.

Filed Sept. 14, 1971, Ser. No. 180,542

Term of patent 14 years

Int. Cl. D27—03

U.S. Cl. D85—2 H

FIG. 3

FIG. 4

FIG. 1 is a top plan view of an ash tray, showing my new design;

FIG. 2 is a side elevational view, the appearance being the same from all sides;

FIG. 3 is a bottom plan view; and

FIG. 4 is a cross-sectional view, partly in side elevation, taken on line 4—4 in FIG. 1.

I claim:

The ornamental design for an ash tray, as shown and described.
